United States Patent Office.

JAMES RILEY, OF CHICAGO, ILLINOIS.

Letters Patent No. 92,365, dated July 6, 1869.

IMPROVED RAILWAY-CAR COUPLING.

The Schedule referred to in these Letters Patent and making part of the same.

To all whom it may concern:

Be it known that I, JAMES RILEY, of Chicago, in the county of Cook, and State of Illinois, have invented an Improved Car-Coupling; and I do hereby declare that the following is a full, clear, and exact description thereof, which will enable others skilled in the art to make and use the same, reference being had to the accompanying drawings, and letters marked thereon, making a part of this specification, in which—

Figure 1 is a perspective representation of my improved car-coupling.

Figure 2, a perspective representation of the elongated catch removed from the other parts.

Figure 3, an elevation of the coupling, with one draw-bar removed.

Figure 4, a perspective view of one of the coupling-pins, removed.

Figure 5, a plan view of the jaws, so broken away as to show the spring which holds them fast to the pin.

Figure 6, a view of the under side of the devices for supporting the lower end of the lever.

The present invention relates to an improvement in that class of couplings which are designed to act automatically; and

Its nature consists in the use of jaws, which are opened by a lever, placed between them and pivoted to a bar, which is held in place by a strong staple and lugs; and, in combination with the foregoing, an elongated catch and bumpers, the latter projecting out far enough from one of the draw-bars for the jaws to operate between them.

A B represent the draw-bars, which may have any length for the convenience of fastening them to the cars.

The draw-bar B has a horizontal slot in its inner end, of suitable size to receive a lug, N, projecting out from the elongated catch L, said bar and lug having mortises through them to receive a pin, C, figs. 1 and 4.

This pin is so recessed out at E E as to be held in place by the strain on lug N when the cars are in motion.

The draw-bar A has a horizontal slot made in it, of suitable size to receive the pivoted ends G of the jaws F, which are held in said draw-bar by means of a pin, C, figs. 1 and 4, put through a hole, X, formed by cut-

ting notches in the inner sides of the jaws F, as shown at fig. 5.

A mortise, I, having an angular end, Y, is formed by notching out the jaws F, for the purpose of receiving a lever, T, which is held in place by a pin, K, and so bevelled off on the sides at J as readily to open the jaws F, as seen by dotted lines Z, fig. 5; when the upper end of the lever is moved in the direction indicated by the dart a, and thus release the notched ends H H from the catch L.

The lower end of the lever is pivoted to a bar, V, which is held in place by a staple, W, rigidly fastened to the under side of the draw-bar A, and strengthened by lugs U, through which the staple passes, and which are bolted fast, at their opposite ends, to the draw-bar A.

Bumpers P are rigidly attached to the inner end of the draw-bar A, and have projecting arms Q Q diverging from each other, for the purpose of giving to their strong end piece R such length as will strike the draw-bar B when cars of different heights are to be coupled.

The catch L is also elongated above and below the draw-bars for this purpose.

If it should become necessary to operate the coupling from the tops of cars, levers can be readily attached to an eye, d, on the upper end of lever T.

At fig. 5, a part of the jaws F, is broken away, to show a coil-spring, e, which locks the notched ends H H over the catch L.

The ends of this spring are provided with screws f, which hold in those parts h of the jaws F enclosing the ends of the slot in which the spring is placed.

By means of this construction and arrangement, an automatic car-coupling is provided, which is not likely to get out of order, and which can be operated very conveniently, and at the same time practically answer the purpose designed.

Having thus described my invention,

What I claim, and desire to secure by Letters Patent of the United States, is—

The draw-bars A B, bumpers P, jaws F, elongated catch L M, lever T, bar V, and lugs U, when constructed, combined, and arranged as described.
